(57) **CLAIM**

The ornamental design for a lighting fixture, as shown and described.

DESCRIPTION

1. Lighting fixture
- 2.-3. Parts of lighting fixture
- 1.1 : Perspective
- 1.2 : Front
- 1.3 : Right
- 1.4 : Back
- 1.5 : Left
- 1.6 : Top
- 1.7 : Bottom
- 2.1 : Perspective of an enlarged detailed element of lighting fixture
- 2.2 : Front
- 2.3 : Right
- 2.4 : Back
- 2.5 : Left
- 2.6 : Top
- 2.7 : Bottom
- 3.1 : Perspective of an enlarged detailed element of lighting fixture
- 3.2 : Front
- 3.3 : Right
- 3.4 : Back
- 3.5 : Left
- 3.6 : Top
- 3.7 : Bottom

The broken lines in the drawings illustrate portions of the lighting fixture which forms no part of the claimed design.

1 Claim, 21 Drawing Sheets
